UNITED STATES PATENT OFFICE.

REID G. FORD, OF BROOKLYN, NEW YORK, ASSIGNOR OF ONE-TENTH TO WILLIAM J. BARKLEY, OF BOSTON, MASSACHUSETTS.

RECORDER FOR TELEGRAPHIC MESSAGES.

1,267,068.

Specification of Letters Patent.

Patented May 21, 1918.

Application filed January 21, 1916. Serial No. 73,303.

To all whom it may concern:

Be it known that I, REID G. FORD, a citizen of the United States, residing in the city of New York, borough of Brooklyn, in the county of Kings and State of New York, have invented a new and Improved Recorder for Telegraphic Messages, of which the following is a specification, reference being had to the accompanying drawings, in which—

Figure 1 is a section, partly in elevation, showing apparatus embodying my invention; Fig. 2 is a plan of the apparatus contained in the casing; Fig. 3 is a side elevation of the tape-feeding mechanism; Fig. 4 is an end elevation thereof; Fig. 5 is a vertical section of the tape-supporting mechanism; Fig. 6 is a detail of the drum upon which the unused tape is mounted, and Fig. 7 is a diagram of the electric circuits, showing their relation to the operative parts of my apparatus.

My invention relates to recorders for telegraphic messages, particularly on wireless systems, and consists in mechanism connected with the sending instrument by which a complete record of all messages sent is automatically taken. My invention is particularly useful in connection with sending instruments on board ships, and enables a complete record to be taken of every message sent. The mechanism is contained in a sealed or locked box, which prevents the operator from tampering with the apparatus and thus interfering with the reliability of the record taken. In this way, not only is a complete record of every message kept, but it compels compliance with the regulations and shows whether the operator is efficient or inefficient. My invention also consists in the construction and operation of the parts which I shall hereinafter describe and claim.

Referring to the drawings, 2 indicates a container or box for the operative parts of the mechanism which I am about to describe, having secured thereto the standards 3, upon which is mounted a tape-supplying drum 4 supporting a roll of tape 6 of blank recording paper, and a second or receiving drum 5, upon which the tape 6, after the messages have been recorded upon it, is intended to be wound. From the drum 4 the tape 6 is led through a slot 7 into the interior of the container. Within the container the tape passes through a punch guide 8,

in which the messages are intended to be impressed on the tape, then around the idler pulley 9 to the driven pulley 10, by which the tape is fed forwardly. It then passes around the idler 11, out of the box, through the slot 12, and over the surface of the tape on the drum 4, around the idler 13 positioned between and in contact with the drums 4 and 5 or the tape on the drums, 65 and thence onto the drum 5. When the tape has been attached to the drum 5 and is being fed off of the drum 4, the movement of the drum 4 will drive the idler 13 in the opposite direction, and the drum 5 70 will in turn be oppositely driven by the idler 13, so that, as the tape feeds from the drum 4, it will automatically wind up the tape on which a record has been impressed on the drum 5.

The tape-impressing mechanism, as is shown in Figs. 1, 2 and 7, preferably consists in a frame 8, which has at one end a die 14, across which the tape travels through the slot 15 in the guide. Mounted 80 to reciprocate in suitable bearings in the guide 8 is a punch 16, having a spring 17 thereon. As the spring 17 bears at one end against the frame and at the other end against a collar 18 on the punch 16, it will 85 normally hold the punch away from the tape and die 14, across which the tape travels. The actuating mechanism for the punch consists in a pair of magnets 19, by which an endwise pull is exerted on an 90 armature 20, which, when so actuated, moves forwardly and strikes the rear end of the punch 16, forcing it forwardly against the compression of the spring 17, to strike and perforate the tape against the 95 die 14.

The mechanism for feeding the tape, as is shown in Figs. 2, 3 and 4, consists in the driven pulley 10 fixed to a shaft 21, which has also loosely mounted thereon a ratchet 100 gear 22. Keyed to the shaft 21 is a bushing 23, and connecting the bushing 23 and the gear 22 is a spiral spring 24, by which motion imparted to the gear 22 is transmitted to the shaft 21, and by it to the pulley 10. 105 Also loosely mounted on the shaft 21 is an arm 25, which carries a pawl 26 by which the gear is rotated. The arm 25 is supported at its outer end by a spring 27, which permits the arm 25 to be reciprocated vertically and thereby actuate, through the pawl 26, the gear 22 by its toothed engagement 110

therewith. The gear 22 is held from counterclockwise movement by a pawl 28. The mechanism for reciprocating the arm 25 consists in an L-shaped member 29, which 5 is secured to the armature 30 and, as electrical current is applied to the magnets 31, the armature 30 will draw down by its L-shaped piece 29 the arm 25, and will thus actuate the gear 22 through the pawl 26.

10 To enable the shaft 21 to operate at a substantially constant speed, I employ a governor, as is shown in Figs. 2 and 3, which consists in a sleeve 32 loosely mounted on the shaft 21, a collar 33 secured to one 15 end of the sleeve, a collar 34 loosely mounted on the other end of the sleeve, and a disk 35 attached to the collar 34. Secured to the collars and about the sleeve are a plurality of flat plate springs 36, of which I have 20 shown three. Attached to the plate springs 36 at their middle portions are weights 37. Motion is transmitted from the gear 38 on the shaft 21 to the gear 39 on the sleeve 32 by the speed-increasing gears 40 and 41, 25 which are mounted on the shaft 42. When the shaft 21 is set in motion it will be seen that the sleeve, through the gears 38, 39, 40 and 41, will be driven at a much higher rate of speed, and as the sleeve revolves the 30 weights 37 will move outwardly and will thus draw the disk 35 against the friction stop 43, which will prevent too high speed being attained, and in this way the speed of the shaft 21 will be regulated. The speed 35 at which the shaft 21 rotates may be regulated by making the stop 43 adjustable relative to the disk 35.

The parts which I have now described are 40 preferably operated in connection with the usual alternating current sending circuit, such as I have indicated at A, the energy to which is supplied by the alternating current generator 45, as is shown in Fig. 7. The sending key is indicated at 46.

45 Having now set forth a construction embodying my invention, I will now describe its operation, which is best shown in Fig. 7.

When, in the act of transmitting, the key 46 is closed, the path of the current leads 50 through the relay 47, actuating such relay and thus controlling the local circuit B, through which the tape-punching and tape-driving mechanisms are actuated. Thus, when the key 46 is closed and relay magnet 55 47 is energized, the path of the current in circuit B leads through battery 48, magnet 19, armature 20, plunger and frame 49, magnet 31, arm of relay 47, thus completing the circuit. With the closing of the local 60 circuit B the tape-punching magnet 19 and driving magnet 31 are actuated simultaneously. The armature 20 moves forwardly and drives the punch 16 through the tape 6, and the armature 30 moves downward 65 and rotates the pulley 10, as is hereinafter

described. When the armature 20 has driven the punch 16 through the tape, the path of the current will then be interrupted at the contact point 51, in that the L-shaped member attached to the armature 20 will 70 have moved away from the plunger 49. The local battery circuit 48 then being open, armatures 20 and 30 will be simultaneously returned to their original or normal position through the actions of springs 17 and 75 27. The armature 20, in returning to its original position, will reestablish the local circuit B by closing the circuit at 51, and reenergize the magnets 19 and 31. The opening and reestablishing of the circuit as 80 above described will cause a quick succession of blows of the punch through the tape, so that, if the sending stroke is long continued, an elongated slot will be cut in the tape, the length of the slot being determined 85 by the duration of the time during which the key 46 is held down. The record made on the tape will correspond to the signals which are being transmitted.

Each interruption of the circuit B, occasioned between the armature 20 and the plunger 49, is reproduced with regard to the magnets 31 by the actuation of the armature 30, so that for each such interruption there is a consequent actuation of the 90 arm 25 and the pawl 26, to rotate the gear 22 in a clockwise direction. As described above, the gear 22 is loosely mounted on the shaft 21, and the connection between the shaft 21 and the gear 22 consists in the 100 spring 24 which, with each movement of the gear when actuated by the armature 30, stores up power for actuation of the shaft 21, the speed of which is regulated by the 105 governor.

To insure a correct record of all signals transmitted and particularly to prevent the operator from tampering with the mechanism and thereby interfering with a proper record being taken, I provide a short circuit device, which prevents the transmission of signals while the mechanism is inoperative. The mechanism used in connection with the short circuiting device consists in an idler 9, mounted on a pivot bar 53, which is normally maintained in lowermost position by the weight of the idler at one end and the upward pull of the spring 54 near its opposite end. If the end of the tape is reached, or if the tape jams on the drum 4 and, at 115 the same time, continues to be fed forwardly by the driven pulley 10, the tape 6 will lift the bar 53 and bring its rear end into bearing with the contact 55, thereby completing the supplementary circuit C around the 120 sending key and short-circuiting it. The whole device will thus be out of action until the tape is freed sufficiently to permit the idler 9 to drop to normal or lowermost position. For the purpose of increasing or 125 130

relieving the tension on the tape I employ a set screw 56, by which the bar 53 and the idler 9 may be raised or lowered.

In Fig. 6 I have shown the drum 4 provided with a flap or strip 52, by which the end of the recording tape 6 is intended to be secured to the drum, so that when a roll of tape has become exhausted, the tape, as it cannot feed forwardly, will bring the short circuiting device into operation and cause the transmitting apparatus to become and remain inoperative until a new roll has been provided and secured at one end to the old tape and at the other end to the flap 52.

In that most radio transmission sets employ an alternating current of electricity of very high frequency, and in that very little magnetic energy can be obtained from such a source of energy, I employ a relay 47, through which the key 46 controls the local circuit B.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In a device for recording telegraphic messages a circuit containing a sending instrument, a recording tape and a tape-impressing means, a secondary circuit controlled by the closing of the first circuit containing electro-magnetic means for actuating the tape-impressing device, a supplementary circuit adapted to be connected with the first-named circuit, and means operated by the tape for utilizing the supplementary circuit and thereby effecting the operation of the sending instrument when the tape ceases to feed normally.

2. In a device for recording telegraphic messages, a circuit containing a sending instrument, a recording tape and a tape-impressing member; a secondary circuit, controlled by the closing of the first circuit, containing electro-magnetic means for actuating the tape-impressing device, an open supplementary circuit adapted to be connected with the first-named circuit, and means operated by the tape for closing the supplementary circuit and thereby short-circuiting the sending instrument, when the tape ceases to feed normally.

3. In a device for recording telegraphic messages, a circuit containing a sending instrument, a recording tape, a tape-impressing member and a tape-feeding device, and a secondary circuit, controlled by the clos-

ing of the first circuit, containing electro-magnetic means for actuating the tape-impressing member and other electro-magnetic means for actuating the tape-feeding device.

4. In a device for recording telegraphic messages, a sending instrument, a container inclosing a tape-impressing member and a tape-feeding device, a roll of tape mounted on the outside of the container and adapted to be fed through the container and the tape-impressing member by the tape-feeding device, and means for withdrawing the tape from the container after the messages sent have been impressed upon it, said container comprising means for preventing tampering with the tape-impressing and tape-feeding devices.

5. In mechanism for recording telegraphic messages, a recording tape, tape-feeding means comprising a pulley driven by a shaft, a gear, and a yielding connection between the gear and the shaft, and electro-magnetic means for actuating the pulley shaft through the gear.

6. In mechanism for recording telegraphic messages, a recording tape, tape-feeding means comprising a pulley driven by a shaft, a gear, a yielding connection between the gear and the shaft, and a governor on said shaft to regulate the speed thereof, and means for actuating said gear.

7. In mechanism for recording telegraphic messages, a sending instrument, a drum having a roll of tape mounted thereon, a tape-impressing member and a tape-feeding device, and means for preventing the feeding of the tape through the mechanism when the end of the tape has been reached, said means consisting of a connection between the end of the tape and the drum.

8. In mechanism for recording telegraphic messages on tape, a sending instrument, means for feeding the tape, and means controlled by the tape for short-circuiting the sending instrument upon a failure of the tape to feed normally.

9. In mechanism for recording telegraphic messages on tape, a tape-impressing member comprising a spring-pressed punch, a spring-pressed plunger, and an armature adapted to reciprocate the punch and the plunger alternately.

10. In mechanism for recording telegraphic messages on tape, a sending instrument, a tape-feeding mechanism comprising a pulley driven by a shaft, a gear, a yielding connection between the gear and the shaft, and means controlled by the sending instrument for actuating the pulley shaft through the gear.
